SPRING HAND GRIPPING CONTROL GARMENT HANGER CONSTRUCTION

Joseph Blumenstein, Cold Spring Harbor, N. Y., assignor to "Sur-Grip" Inc., New York, N. Y., a corporation of New York

Application March 22, 1950, Serial No. 151,280

2 Claims. (Cl. 223—95)

1

This invention relates to garment hangers for suspending trousers, slacks, skirts and the like, and more particularly is directed to spring actuated, hand-gripping control improved constructions of wearing apparel accessory articles of the character described.

Among the objects of the invention is to generally improve articles of the character described which shall comprise few and simple parts that are easily and neatly assembled to provide an attractive balanced wardrobe accessory, which shall be cheap to manufacture, which shall be easy to manipulate, which shall be accident-proof, and which shall be practical and efficient to a high degree in use.

Other objects of this invention will in part be obvious and in part hereinafter pointed out.

The invention accordingly consists in the features of constructions, combination of elements, arrangement of parts hereinafter described and of which the scope of application will be indicated in the claims following.

In the accompanying drawing in which possible illustrative embodiments of the invention are shown:

Fig. 1 is a perspective view of a garment hanger construction embodying the invention, formed principally of sheet metal.

Fig. 2 is an end elevational view of the improved construction shown in Figs. 1 and 3.

Fig. 3 is a front elevational view of the garment hanger shown in Fig. 1, partly broken away to expose the interior assembly.

Fig. 4 is a front elevational view similar to Fig. 3 showing modified improved construction formed with metal tubing portion instead of sheet metal, partly broken away to expose the interior assembly, and

Fig. 5 is an enlarged cross-sectional view of the improved construction taken on lines 5—5 in Fig. 4.

Referring in detail to the drawing 10 denotes a garment hanger construction for suspension of trousers, slacks, skirts, and the like, embodying the invention. Said hanger construction 10 may be formed of two telescopingly slideable members 11 and 12 which, as seen from Figs. 1 to 3, may each be made of sheet metal folded over and bent into an annular cross-sectional structural shape to provide tubular length portions 11a and 12a, respectively, here shown to be circular in shape, with the member portion 11a slideable into and mounted to be extended with respect to member portion 12a.

Member 12 may have an outer end 12b of por-

2

tion 12a terminating in a suitable integrally formed garment engaging means, such as spaced apart depending spread retainers 12c. Likewise member portion 11a may be provided on an outer end portion 11b terminating in a similar integrally formed garment engaging means, namely, depending spread retainers 11c, said retainers 11c and 12c being positioned on opposite end of hanger 10, in parallel alignment with respect to each other. Mounted for pivotal movement to upstand from mid-portions of said members 11 and 12 to extend in the opposite direction to and in substantially the same plane of spread retainers 11c and 12c, there may be provided hand grip levers 11d and 12d. Said lever 11d through spaced offset ears 11e formed at one end thereof span and connect by means of through or rivet pin 11f, with tubular length portion 11a of member 11 at a mid-length thereof, elongable closed-ended aligned slots 12g being provided on opposite sides of tubular length portion 12a of member 12 to clear said pin 11f as a limiting alignment guide for member 11 in telescoping movement thereof into member 12. The closed end 12n of said slots 12g may serve as positive limiting stops, at maximum extension of said member 11 with respect to member 12 as is clear from Figs. 1 and 2.

The other end of lever 11d opposite ears 11e may also be provided with spaced ears which swingably connect by a hinged means formed by through or rivet pin 10a with interfitted terminal ears 11h of lever 12d. The other end of lever 12d may also be provided with spaced offset spanning ears 12h swingably connected by means of through or rivet pin 12f with a mid-length of said tubular length portion 12a, as shown in Figs. 1 and 2.

A suitable compression spring 13 may be positioned within the telescoping slideable members 11 and 12 to extend in abutment with pins 11f and 12f for normally urging maximum separation or extension movement of member 11 and 12 with spread retainers 11c and 12c, respectively.

As it is desirable to provide a suspension support engaging means for hanger 10 to conveniently and quickly detachably securing same in a wardrobe clothes closet or the like, there may be provided a suitable hook 14 extending up from the hinged connection of said hand grip levers 11d and 12d at pin 10a. As seen from Figs. 1 to 3 said hook 14 may be integrally made to extend outwardly upward from grip lever 12d beyond said hinged connection provided by pin 10a, said hook 14 preferably being positioned and

curve shaped so that when said hook 14 is hung in a wardrobe closet or rack support hanger 10 with or without a garment said hanger 10 will be suspended in a balanced state with slide members 11 and 12 extending substantially in a horizontal plane.

Lever 11d and 12d may each be formed with suitable finger and hand contour portions 11m and 12m, respectively, for comfortably accommodating the hand gripping operation in the manner hereinafter described.

From the above description and drawings the practical utility of hanger 10 will be apparent. After constructing the parts described above and assembling same as shown in the drawing, by applying a hand squeeze action on gripping levers 11d and 12d, said levers will pivot on pins 10a, 11f and 12f and tubular member 11 will be telescoped into member 12 with the ear ends 11e and 12h swinging toward each other against the action of spring 13 bearing on pins 11f and 12f. This hand squeezing operation brings spread retainers 11c and 12c in closed aligned relation so that the latter may be readily inserted into cuffed bottom openings B of trouser T in the well understood manner. Releasing the hand grip on levers 11d and 12d will permit spring 13 to cause members 11 and 12 to be extended up to the limited movement permitted by pin 11f striking on slot end 12g. By making the maximum expandable distance between the spread retainers 11c and 12c adjustable for a range of various trouser bottom sizes corresponding to the width of folded trouser bottom openings B, trouser T having bottom opening B within such range will be releasably engaged by said retainers 11c and 12c and suspended in a desired trouser position free from wrinkling as is clear from Fig. 1.

In order that accident-proof hand grip on levers 11d and 12d be provided, said levers may have their longitudinal edges formed with in-turned rounded flanges, that is, U-shaped in cross-section, and all other moveable parts shielded to make manipulation thereof safe and free from causing possible injury even when carelessly handled.

To make spread retainers 11c and 12c more effective to engage in the trouser openings B, said retainers may from outer facing edges of each be provided with spaced apart notches 11k and 12k, respectively.

A modified construction embodying the invention is shown in Fig. 4 in which hanger 20 is constructed of tubular length portions 21a and 22a of pipe or tube stock instead of bent sheet material above described for hanger 10 and grip levers 21d and 22d of said hanger 20 being made similar to hand grip lever 11d and 12d, respectively, and pins 21f, 22f and 20a like pins 11f, 12f and 10a respectively, with compression spring 23 positioned between pins 21f and 22f, and pin 21f being slidably mounted in elongated slots 22g.

Said grip lever 22d may also be elongated beyond pin 20a to provide extending hook 24.

Spread retainers 22c for hanger 20 may each be clip shaped having a bight 22p and a neck portion 22q, the latter being closely fitted into slits 22r and 21r provided in outer ends 21b and 22b of members 21 and 22, respectively, the bight 22p being shaped and sized to snugly conform to the inner cross-sectional shape surfaces of said members 21 and 22 and secured in assembled

position as shown in Fig. 4 by spot welding or in other well understood manner.

Garment hanger 20 may be used and operated like hanger 10 described above and shown in the drawings.

It will thus be seen that there is provided improved garment hangers in which the several objects of the invention are achieved and which are well adapted to meet the conditions of practical use.

As various possible embodiments may be made of the above invention and as various changes may be made in the embodiments above set forth, it is to be understood that all matters herein set forth and shown in the accompanying drawing are to be interpreted as illustrative and not in a limiting sense.

Having thus described my invention I claim as new and desire to secure by Letters Patent:

1. A garment hanger comprising a pair of elongated member portions assembled for telescoping movement, one of said member portions into which the other member portion extends having elongated aligned slots located over a mid-section of said other member, hand gripping levers each formed of a relatively rigid structure secured to extend from said member portions, a hinge pin swingably interconnecting ends of said levers, spaced apart pins for pivoting the other ends of said levers, one pin passing through a mid-section of the first mentioned member portion and the other pin through said mid-section of the other portion and through said slots, a compression spring mounted within the telescoping assembly of said member portions to extend and exert pressure therebetween for urging said member portions into a maximum extensible relation, and parallelly aligned spread retainer garment engaging means supported at opposite free ends of said member portions.

2. A garment hanger comprising a pair of extensible tubular member portions telescopingly assembled, one of said member portions having elongated aligned slots located to lie in the region of the mid-section of the other member, compression spring means mounted within said portions urging the latter into maximum extensible relation, hand gripping levers each formed of a relatively rigid structure hinged together for swinging movement at one end of each and pivoted at the other end to spaced apart mid-sections of said member portions for retracting the latter from said maximum extensible relation, said levers having extending ears receiving pivot pins for said hinging together and for pivoting said levers to said member portions, one of said pins passing through said aligned slots, spread retainer garment engaging means terminating said member portions, and a hook shaped extension for one of said levers beyond said hinged end for suspending the hanger.

JOSEPH BLUMENSTEIN.
